CLAIM

The ornamental design for a mammogram marker, as shown and described.

DESCRIPTION

FIG. 1 is a top plan view of a mammogram marker showing my new design;

FIG. 2 is a front elevation view thereof, the rear being identical to the front; and,

FIG. 3 is a left side elevation view thereof, the right side being identical to the left.

The bottom of the mammogram marker is flat and is devoid of surface ornamentation.
